CLAIM

I claim the ornamental design for a socket set, as shown and described.

DESCRIPTION

FIG. 1 is a front, right and top perspective view of a socket showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, left and bottom perspective view thereof, showing the socket being mounted on a mounting bracket; and,

FIG. 10 is a rear, left and top perspective view thereof, showing the socket being mounted on the mounting bracket. In FIGS. 2 and 4 the broken lines are for the purpose of illustrating portions of the socket that form no part of the claimed design. Additionally, in FIGS. 9 and 10 the broken lines are for the purpose of illustrating environment only that form no part of the claimed design.
